DRIVING ARRANGEMENTS
Kristen Hedegaard, Holsteinborgvej 18,
Copenhagen, Denmark

Continuation of application Ser. No. 277,880, Mar. 21, 1952. This application Dec. 6, 1957, Ser. No. 701,696. Claims priority, application Denmark, Mar. 30, 1951, 974/51

66 Claims. (Cl. 112—219)

The present application is a continuation application of my copending application Serial No. 277,880, filed March 21, 1952, now abandoned and entitled "Driving Arrangement."

The present invention relates to driving arrangements. More specifically the present invention relates to driving arrangements of the unitary type and preferably driving arrangements of the kind normally known in the trade as clutch motors or motors of the clutch-and-brake type.

The invention also relates to driving arrangements of the clutch-and-brake type such as, for instance, used in sewing machines for the clothing industry without, however, being confined to sewing machines.

In sewing machines for private or private or domestic use the velocity of the machine does not play an important role. In the use of sewing machines for the ready-made clothing industry it is necessary, however, to run the machine at a high speed and this high speed must be obtained instantaneously with the start of the machine. Therefore, in such sewing machines the driving spindle runs continuously and a clutch mechanism is used for coupling the sewing mechanism to the continuously rotating driving spindle. Thus, the sewing machine will run at full speed substantially immediately after shifting of the clutch to the driving position thereof.

In order to stop the sewing machine as instantaneously as it is started, a clutch is arranged to be shifted to engage a brake member. The machine will, therefore, also stop substantially instantaneously.

The position of the movable parts of a sewing machine of the prior art, however, is usually incidental, i.e., not preselected, when the sewing machine is stopped. This is a disadvantage because in some cases in order to turn the work about the needle, the latter must be in the down position thereof, when the machine is stopped, while in other cases the needle must be in the raised position thereof, as, for example, in order to remove the work from the machine.

The usual way of correcting for the wrong position of the needle when the machine is stopped is to rotate the balance wheel of the machine by hand. Such a manual correction is, however, irrational and time-wasting. It requires the operator to remove one hand from the work. A time analysis will show that the waste of time due to such manual needle adjustment may run up to approximately twenty-five percent or more of the total working time.

It is, therefore, an object of the present invention to provide a driving arrangement of the clutch-and-brake type, which will enable full control with the driven machine, such as a sewing machine, with the further possibility of stopping the latter when the movable parts thereof are in a desired or preselected position.

It is a further object of the present invention to provide a clutch-and-brake driving arrangement which enables a further predetermined movement of the machine which is continued to be driven after having shifted the clutch from engagement with the driving spindle to engagement with the brake member.

It is a further object of the present invention to provide a unitary driving arrangement which can be generally applied to any existing or new machine and which is

2

capable of operating as a high-speed drive means or a low-speed drive means and which is also adapted to stop the driven machine with the movable parts thereof in a desired or preselected position when used as a low-speed drive means.

Another object of the present invention resides in providing a clutch-motor having a brake member which is capable of operating as a combined high-speed and low-speed drive means for a driven machine.

10 It is still a further object of the present invention to provide a driving arrangement of the type specified which will enable an automatic stop of the driving arrangement when the movable part of the machine, such as, for instance, the stitch-forming mechanism of a sewing machine, is in at least one predetermined position.

15 A further object of the present invention is to provide a driving arrangement in which the machine can be stopped with the movable parts in one of a plurality of predetermined positions which may be preselected in advance by the operator.

The invention further aims to provide simple and reliable arrangements and operating devices to fulfill the purposes specified hereinabove and other purposes which will appear from the following specification.

20 25 The term "sewing machine," as used in the following specification, is to be interpreted in its broadest sense so as to include not only ordinary sewing machines having a reciprocatory needle, for instance, an upwardly and downwardly moving needle, but any kind of sewing machines designed for special purposes, such as, for example, a padding machine.

25 30 In order that the invention may be more clearly understood, some preferred embodiments thereof will now be described with reference to the accompanying drawings in which:

FIGURE 1 is a perspective view of a sewing machine having a motor arrangement according to one embodiment of the invention;

35 FIGURE 2 is an axial cross-sectional view on enlarged scale through a motor and clutch-and-brake arrangement in accordance with the present invention;

40 45 FIGURE 3 is a schematic diagrammatic view showing the motor arrangement in connection with an automatic control in accordance with the present invention for stopping the sewing machine with the needle in a predetermined position;

FIGURE 4 is an enlarged elevational view of a detail of the arrangement shown in FIGURE 3;

50 55 FIGURE 5 is a schematic diagrammatic view, similar to that shown in FIGURE 3, of a modified embodiment in accordance with the present invention provided with an automatic control for stopping the sewing machine with its movable parts in two different predetermined positions;

55 FIGURE 6 is a schematic wiring diagram showing the circuits in still another embodiment of an arrangement in accordance with the present invention in which the auxiliary drive is reversible;

60 FIGURE 7 is a perspective view of one embodiment of a treadle designed for operating the machine and control arrangement in accordance with the present invention;

65 FIGURE 8 is a schematic diagrammatic view, similar to that shown in FIGURES 3 and 5, of still another embodiment in accordance with the present invention;

FIGURE 9 is a perspective view of one embodiment of the auxiliary drive having a mechanical transmission in accordance with the present invention;

70 FIGURE 10 is a schematic diagrammatic view of a modified embodiment of the arrangement shown in FIGURE 3;

FIGURE 11 is a perspective view of a modified em-

bodiment of the treadle arrangement shown in FIGURE 7;

FIGURE 12 is a schematic diagrammatic view of still another embodiment of the arrangement shown in FIGURE 5;

FIGURE 13 is a schematic diagrammatic view of still another modified embodiment of the arrangement shown in FIGURE 11;

FIGURE 14 is a perspective view of a modified embodiment of the treadle arrangement shown in FIGURE 11;

FIGURE 15 is a schematic diagrammatic view of an arrangement similar to that shown in FIGURE 13 provided with a treadle arrangement as shown in FIGURE 14;

FIGURE 16 is a partial perspective view, with parts thereof broken away, of another embodiment of a switch arrangement including mercury switch tubes;

FIGURE 17 is an axial cross-sectional view of the embodiment shown in FIGURE 16;

FIGURE 18 is a partial plan view of a switch arrangement including a switch as shown in FIGURE 16;

FIGURE 19 is an end view of the switch arrangement shown in FIGURE 18;

FIGURE 20 is a schematic wiring diagram showing an arrangement including a switch as shown in FIGURE 16;

FIGURE 21 is a schematic wiring diagram of a modification of the arrangement shown in FIGURE 20, in which the machine is able to stop in one or two alternative positions;

FIGURE 22 is a schematic wiring diagram of a further modification of the arrangement shown in FIGURE 21 in which the machine is also adapted to be reversed, and

FIGURE 23 is a perspective view of a further modification of the treadle arrangement shown in FIGURES 7 and 11.

Though in the following description the present invention will be explained specifically with reference to a sewing machine, it will be understood that the invention is not limited hereto. As explained hereinabove, the problem of obtaining an essentially instantaneous starting and stopping of the machine is an important problem in connection with sewing machines for the ready-made clothing industry, but it will be understood that the present invention may be used also in connection with other working machines in which the same problem is present.

It will further be understood that though the instant invention, in the following description, is explained in connection with sewing machines having a single driving unit, viz a machine having a separate driving motor, this is not essential to the present invention. The coupling arrangement may equally well be used in connection with machines which are driven from a common driving spindle feeding a plurality of machines. The term "driving motor" or "driving means" when used in the following description should, therefore, be interpreted in its broadest sense so as to encompass any type of power drive including a rotatable driving spindle or driving element.

Referring now to the drawing, wherein like reference numerals are used throughout the various views to designate like parts, and more particularly to FIGURES 1 and 2, reference numeral 10 designates therein a table for a sewing machine 12 having a driving wheel or balance wheel 14. The table 10 is supported by upright frame members or the like 16 and 18 which at their lower ends are connected with one another by means of a cross bar 20. The sewing machine 12 is driven from a motor 26 suspended beneath the table 10 in any suitable manner. The driving means includes a driving cord or belt 22 driven from a pulley 60 on the motor 26. The coupling between the motor 26 and the pulley 60 is controlled by means of the treadle or pedal 143,

which by means of a pull-rod or the like 146 is connected with a pivotable member 66 by means of which a clutch element 62 (FIGURE 2) is shiftable between two positions of engagement thereof with cooperating parts.

5 By means of a further treadle or pedal 152, which is connected to by means of a pull-rod or the like 150 with a switch arm 151 (FIGURE 1) extending from the housing 149 of a switch the operator, after having decoupled or disengaged the motor by means of the treadle 148, as will be explained more fully hereinafter, is able to control the further movement of the sewing machine 12 in such a manner that the machine can be stopped with the needle in a wanted preselected or predetermined position.

The motor, which is shown in greater detail in FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

15 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

20 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

25 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

30 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

35 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

40 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

45 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

50 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

55 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

60 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

65 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

70 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

75 FIGURE 2, may be of any suitable construction having a stationary part 27 and a rotor 29 (FIGURE 2). The rotor 29 is arranged on a spindle 38 rotatably supported in anti-friction bearings 36 and 37, respectively. The right hand bearing 36 is arranged within an interior partition 35. The left hand bearing 37 is arranged in an end cover plate 33. At the opposite end of the motor another cover plate 34 is arranged within which the clutch mechanism is supported. The right hand end of the driving spindle 38 carries a flywheel 40 having in its surface remote from the left hand cover plate 33 a driving clutch element in the form of an annular groove 42 in which is arranged an annular ring or disk 44 of a suitable frictional material, such as, for example, made of fiber.

tively, for selective engagement with the rings 44 and 88, respectively. The annular member 76 is further provided at the circumference thereof with a worm gear 92 meshing with a worm 94, the shaft 96 of which (FIGURES 1 and 27) extends outside the end cover housing 34 and is provided at the outward extension thereof with a pulley 98 (FIGURE 1) which is connected by means of a driving belt 99 with a similar pulley 101 mounted on the spindle of the auxiliary motor 59. It will be understood that instead of arranging the auxiliary motor 59 and the worm 94 on opposite sides of the main driving motor 26, the auxiliary motor 59 may, as an alternative, be placed in direct connection with the worm shaft 96.

The circuit of the auxiliary motor 59 may be selectively closed or opened by means of the switch 149 controlled by the treadle 152 (FIGURE 1).

Operation

The operation of the arrangement so far described is as follows:

The main motor formed by electric motor 27 and 29 is maintained in continuous rotation. By operating the treadle 148 the arm 64 is swung or pivoted by means of the pull-rod 146. This in turn will rotate the bushing 50 operatively connected with pull-rod 146 and due to the engagement between the pin 72 and the helical groove 70 in the bushing 50, any rotation of the bushing 50 will be translated thereby into an axial displacement thereof. The spindle 56 will participate in this axial displacement of bushing 50 and the clutch disk 62 will thereby be shifted between the two extreme positions corresponding to the two engaged positions thereof. In its left hand position the clutch disc 62 is in frictional engagement with the friction ring 44 on the flywheel 40, which thereby couples the driven spindle 58 directly to the motor spindle 38. The sewing machine will thereby be started instantaneously. In its extreme right hand position, the clutch disc 62 will be in frictional engagement with the ring 88 on the brake member 76. This results in an instantaneous stopping of the sewing machine. If the position of the movable parts, primarily the needle of the sewing machine, when stopped instantaneously, is not the wanted position, a correction can be made by means of the auxiliary motor 59. This motor may, as shown in FIGURE 1, be started at will by operating the treadle 152 and thereby operating the switch 149 in the auxiliary circuit. The auxiliary motor 59 when started drives by means of belt 99 the worm shaft 96 which in turn rotates the worm wheel 76 and will thereby rotate, at a relatively slower speed, the clutch disk 62, which is in frictional engagement with the annular friction ring 88 of the flange 82 connected with worm wheel 92. Thus, a relatively slow or slower movement will be imparted to the sewing machine by suitably operating treadles 148 and 152. The speed is so adapted that the operator is able to stop the machine by operating the treadle 152 when the needle is in the wanted position by selectively breaking the circuit of the auxiliary motor 59.

Instead of the above-described method of control for the selective closing and breaking of the circuit of the auxiliary motor 59 at the will of the operator, the present invention may be modified to provide an automatic control by means of which the sewing machine may be stopped automatically with the needle in one or more predetermined positions, for instance, in the top position or in the down position thereof.

One embodiment in which the needle is automatically stopped in a predetermined position is shown in FIGURES 3 and 4. In FIGURE 3, a three-phase main motor 26 is shown having feed leads A, B and C. The auxiliary motor 59 may, for instance, in a manner which will be more fully described with reference to FIGURE 6, be inductively supplied from the stator of the main

motor 26. It will be understood that by feeding the auxiliary motor 59 inductively from the stator of the main motor 26, it is possible to feed the auxiliary motor 59 with relatively low voltage so as to enable the use of more simple switches in the circuit of the auxiliary motor 59 and to avoid any danger. The supply leads of the auxiliary motor are designated by reference characters a, b and c. The breaking of the supply circuit for the auxiliary motor 59 is effected in two of the phases, viz the leads b and c by means of switches of which, in order to simplify the drawing, only one switch 202, arranged in the phase lead b, is shown. This switch 202 consists of a fixed contact spring 204 and a movable contact spring 206, the latter being carried by a pivoted arm 208. The contacts are arranged in a housing 210 shown schematically only in which the contact spring 204 is firmly secured, for instance, on a relatively fixed support 205. The arm 208 is pivoted in a bracket 212 in the housing 210. The arm 208 projects through an aperture 214 in the housing and the end 209 of the arm extends in the path for a cam member 216 which may be arranged within the periphery of the flywheel 218 of the sewing machine 12. This cam member 216 will constitute means for selectively operating, for instance, operating the switch within a certain portion of its path, viz in a certain position of the actuating mechanism of the machine.

To prevent the cam member 216 from engaging the end 209 of the arm 208 during each revolution of the flywheel 218, which would give rise to an undesirable noise during the operation of the machine 12, the cam member 216 may, as shown in FIGURE 4, be pivoted on a pin 220 and be influenced by a spring 222, which will resiliently hold the cam member against a stop 224. By including in the cam member a suitable weight it will be possible, by means of centrifugal force, to keep the cam member 216 in the position shown in FIGURE 4 in dotted lines during normal full-speed operation of the sewing machine 12. In this position the cam member 216 will no longer be in the path of the end 209 of the contact arm 208.

Operation

The arrangement shown in FIGURE 3 operates in the following manner:

The auxiliary motor 59 will be running continuously during the operation of the main motor 26, the motor circuit being normally closed through the switch 202. When the main motor 26 is decoupled and the clutch member 62 is brought, by means of the treadle 148, into engagement with the brake disk 76 (FIGURE 2), the sewing machine 12 is driven by means of the auxiliary motor 59 but at a relatively slow speed. At this stage, the spring 222 will press the cam member 216 inwardly into engagement with the stop 224, and in this position the cam member 216 will cooperate with the end 209 of the contact arm 208 and thereby raise this arm to open the switch 202 so as to brake the driving or energizing circuit for the auxiliary motor 59. The position of the cam member 216 in the flywheel 218 is such that the breaking or opening of the auxiliary motor energizing circuit takes place with the needle of the sewing machine 12 in a predetermined position, for example, in the high position.

It will also be possible to arrange the circuit in such a manner that the needle of the sewing machine can be stopped automatically at will either in the high position or in the down position thereof. An arrangement for this purpose is shown in FIGURE 5. In this embodiment a four line double pole switch generally designated by reference character U is inserted in the two-phase leads b and c. This switch U may be operated, directly or indirectly as indicated, by the treadle arrangement of the machine or by a manually operated device. At the right hand side of this switch, as viewed in FIG-

URE 5, the phase leads are subdivided into two circuits each, each phase lead being divided from the double poles of the switch and designated by corresponding reference characters c' , c'' , b' , b'' . The leads c' and b' are connected in the same manner as the leads c , b in FIGURE 3 through a switch $202a'$, $202b'$ operable by a cam member 216 like the cam member 216 in FIGURE 3.

The leads c'' and b'' are connected in a similar manner through a similar switch $202a''$, $202b''$, which is also so arranged as to be operated by the same cam member 216, but is located diametrically opposite to the switch $202a'$, $202b'$. It is obvious that the switch U constitutes means for selecting which of the two switches $202a'$, $202b'$ or $202a''$, $202b''$ will break the auxiliary motor circuit.

In this embodiment, the switches are of the type used in telephone or like installations. One of the contact springs, in the embodiment illustrated the top spring of switch $202a'$ and the bottom spring of switch $202b''$, are provided with extensions $209'$ and $209''$, respectively. The switches are constructed in such a manner that lifting of these extensions of the springs will not only lead to the opening of either of the two switch portions $202a'$ and $202b''$, but will also effect a simultaneous opening of the other switch portions $202b'$ or $202a''$.

It will be understood from FIGURE 5 that in the top or raised position of the switch U, as illustrated, the lower double switch $202a'$, $202b'$ is inserted in the feed circuit of the auxiliary motor 59 so as to enable the sewing machine to be automatically stopped with the needle in one position, for example, the down position. By changing the switch U over, the top switch $202a'$, $202b''$ is substituted in the auxiliary motor circuit for the previously mentioned switch $202a'$, $202b'$ so as to enable the sewing machine 12 to be automatically stopped with the needle in the opposite position, for instance, the top position thereof.

In FIGURE 6 is shown a diagram of an alternative arrangement which may be operated either automatically or manually. As in FIGURES 3 and 5, the supply leads for the main motor 26 are designated by A, B and C. The motor 26 is a three-phase motor having stator coils A₁, B₁ and C₁. Further coils a₁, b₁ and c₁ are inductively coupled to the main motor stator coils A₁, B₁ and C₁ so as to feed inductively the auxiliary motor 59 through supply leads a, b and c. The stator of the auxiliary motor 59 is designated by a', b' and c'. Preferably the voltage for the auxiliary motor 59 is transformed down to lower voltage, for instance 24 volts.

A double pole reversing switch, generally designated by reference character O, is inserted into the phase leads a and c which has three positions. The intermediate or center position of the switch O corresponds to breaking or opening the two phase leads a and c and thereby breaking or opening the auxiliary motor supply circuit to stop the auxiliary motor 59. The two exterior or outer positions of the switch O correspond to a direct or reverse connection of the two-phase leads a and c, respectively, to enable the auxiliary motor 59 either to run forwardly or to be reversed.

With the arrangement shown in FIGURE 5, as well as with that shown schematically in FIGURE 6, a treadle arrangement similar to that shown in FIGURE 7 might be used.

In the treadle arrangement of FIG. 7, the main operating treadle similar to 148 is combined with the switch operating treadle 152. More specifically, the switch operating treadle 152 is split up in two parts, each of which is arranged like a subsidiary treadle on the main operating treadle and each of which is adapted to switch on that part of the machine with the needle in one or the other predetermined positions or reverse the motor eventually with subsequent stop in a predetermined position.

The main operating treadle, which by way of example is shown in the form of a rectangular frame, is designated by reference numeral 300. This frame 300 is pivotally mounted on a spindle 302 carried by bearings in brackets

304 and 306 secured to the lower cross bar 20 (FIGURE 1) of the sewing machine rack. This treadle 300 is connected in any convenient manner with the pull-rod or chain 146 leading to the main motor operating arm 64 (FIGURES 2, 3 and 5). It will be understood that by rocking this main treadle 300, the main motor 26 is stopped and started in the same manner as by means of the single treadle 148 in the various embodiments shown and described herein.

Individual treadle plates P_h and P_v are provided on frame 300 which are individually pivotally mounted on common shaft 308 extending within the frame 300 and supported in the side walls thereof.

Between the two treadles P_h and P_v, a spindle 310 is arranged extending through the end walls of the frame 300 and rotatably supported in bearings (not shown) provided therein.

On one end of spindle 310 there is arranged a two-armed lever 312 having upwardly bent ends 312a and 312b adapted to be engaged by either of the two ends of the treadle plates P_h and P_v, the ends 312a and 312b extending above that end wall of the frame 300 nearest to and in which the lever 312 is carried.

At the other end of the spindle 310 there is secured a laterally extending arm 314 adapted to operate the two-position switch used in the auxiliary motor circuit, viz either the switch O of FIGURE 6 or the switch U of FIGURE 5.

In the arrangement shown in FIGURE 7, the switch is arranged on a bracket 316 extending from the rear end of the frame 300. The switch operating arm is provided with a bifurcated portion 318 in which the arm 314 is received.

The switch is not shown in detail and may be of any convenient construction, preferably of the type comprising a tiltably arranged mercury switch tube. Switches of this kind are, however, commonly known and the right type of switch can readily be selected by those skilled in the art.

Operation

The arrangement shown and described with reference to FIGURE 7 operates in the following manner:

By way of example, with reference to FIGURE 5, it is assumed that the sewing machine 12 is to be automatically stopped with the needle in the top position thereof and it is further assumed that the position of the switch shown in FIGURE 7 corresponds to the stop-in-top position.

The operator will then only operate the main treadle by means of the right foot pressing on the right treadle plate P_h. This will keep the switch U in the right position so that when the main treadle 300 is tilted about its spindle 302 to stop the main motor 26, the auxiliary motor 59 will remain energized and continue to run until it is stopped with the needle in the top position thereof.

Correspondingly, if the needle has to be stopped in its lower position the operator will only use the left side treadle plate P_v. By operating the main treadle by means of this treadle plate it will tilt the lever 312 and thereby change over the switch U so as to result in stopping the sewing machine 12 with the needle in the lower position thereof.

Correspondingly, if in some cases reverse motion of the sewing machine 12 is wanted after decoupling the main motor 26, the treadle arrangement may be included in the arrangement shown in FIGURE 6 so that, by operating either of the two extra treadles, the auxiliary motor 59 will drive the sewing machine 12 selectively either in the normal direction or in the reverse direction thereof.

Also a slow continuous motion of the sewing machine can be obtained by the treadle arrangement shown in FIGURE 7.

When the treadle is used, for instance, in the arrangement of FIGURE 5 it will be understood that after having decoupled the main motor 26, an alternative operation

of the two treadle plates P_h and P_v in a manner similar to bicycling will result in a slow movement of the sewing machine 12 with stop alternatively in either top or bottom position of the needle depending on which of the two extra treadles has been last depressed, because each of the two treadle plates will constitute means for selecting that portion of the auxiliary motor circuit which will effect driving the machine 12 half a revolution.

Instead of using, as in FIGURE 3 or FIGURE 5, a centrifugally operated cam 216 to control the breaking or opening of the electric circuit for the auxiliary motor 59, the arrangement may be that shown schematically in FIGURE 8. In this embodiment, the same parts as in FIGURES 3 and 5 are designated again by the same reference numerals.

In FIGURE 8, there is provided on the spindle carrying the sewing machine flywheel 218 a member, generally designated by reference numeral 225, which in FIGURE 8 is shown as a cylinder, but which, within the scope of the invention, might also be a plane disc. Two contact strips 230 and 232, respectively, are provided on this member 225. These strips 230 and 232 are interrupted at 231 and 233, respectively along part of the cylinder surface so as to provide insulating portions between the ends of the contact strips. The leads c' and b' are connected by means of contact brushes to the contact strips at one point of the drum surface and the leads c'' and b'' are in a similar manner connected to the strips by means of contact brushes at a point diametrically opposite thereto.

Operation

In operation, it will be understood that in one position of the switch U of FIGURE 8, the two phases b and c will be broken or opened in a position of the parts of the sewing machine 12 in which the insulated segments 231 and 233 will be in alignment with the contact brushes connected to the leads c' and b' corresponding to stopping the sewing machine, for instance, with the needle in top position thereof, while the sewing machine 12 will be stopped with the needle in the lowest position by changing over the switch U.

While in the foregoing embodiments an auxiliary motor 59 in the form of an electric motor has been described, it will be understood that mechanical driving means may be substituted such as it will now be described with reference to FIGURE 9.

In FIGURE 9 a plate 100 is provided adjacent the end cover 28 of the motor 26. The end of the motor spindle extending through cover 28 is provided with a conical head 30. Brackets 102 and 104, respectively, are provided at each end of plate 100 in which is supported a spindle 106, which is both axially displaceable and rotatable in bearings (not shown) mounted in the two brackets 102 and 104. Cones 108 and 110, respectively, are provided on spindle 106 on each side of the conical head 30. The spindle 106 is extended beyond the bracket 104 and carries on the extension a pulley 112 which is connected by means of a belt 114 with a pulley 98 mounted on the bottom of the spindle 96. Pivoted on pin 116 secured in plate 100 is one arm 118 of a bow-shaped member 120, the right-hand arm 122 of which is pivotally supported on the other end cover of the motor in any suitable manner (not shown). The left hand arm 118 of the bow-shaped member 120 has a projection 124 carrying at its end a roller or the like 126 engaged between a shoulder 128 and a ring 130 provided on spindle 106. The motor 26 is carried by a base plate 132 by means of which it is secured under the sewing machine table. Springs 134 and 136 are connected between this base plate 132 and the bow-shaped members 66 and 120, respectively. These springs 134 and 136 tend to resiliently draw or urge both bow-shaped members 66 and 120 in an upward direction. Furthermore, in a bracket 138 on the plate 100 there is provided a spring 140 acting on a longitudinally displaceable rod

142, the lower end of which is connected with arm 118 by means of a bracket 144 secured to the arm 118.

The bow-shaped member 120 is intended to be connected with the treadle 152 of FIGURE 1. In this embodiment, only an operation of the auxiliary driving mechanism at the operator's will is possible.

Operation

The operation of the embodiment of FIGURE 9 is as follows:

If the sewing machine 12 has been stopped with the needle in an unwanted or undesired position, the operator will use the treadle 152. By operating this treadle 152, which is connected to lower the bow-shaped member 120, the roller 126 is raised with the result that the spindle 106 is displaced axially upwardly. The cone 110 is thereby brought into operative driving connection with the cone 30. The latter being secured to shaft 38 (FIGURE 2) which is in continuous rotation will thereby impart rotation to the spindle 106, which rotation is transmitted through belt 114 and spindle 96 to a worm such as worm 94 (FIGURES 2 and 3), and, in the manner already described in connection with the previous embodiments, will drive the sewing machine 12 at a lower speed. The transmission ratio is so adapted that the speed of the sewing machine 12 when driven by the auxiliary drive is so slow that the machine can be stopped with the needle in the wanted or desired position.

By operating the treadle 152 to raise the bow-shaped member 120, the cone 108 will, in a corresponding manner, be brought into driving connection with the cone 30, which will cause a slow motion of the sewing machine 12 in the opposite direction of rotation.

It will be understood that the spring 140 in connection with appropriate stop means on the rod 142 serves the purpose in the normal position of rest to keep the bow-shaped member 120 in such a position that neither of the two cones 108 or 110 will be operatively connected with cone 30.

Instead of the automatic control for the switches in the auxiliary motor circuit, as shown in FIGURES 3, 5 and 8, a modification thereof may be used as illustrated in FIGURE 10. In this embodiment, only the sewing machine 12 is shown, the circuit being omitted. It will be understood, however, that the arrangement of FIGURE 10 can be used as well in connection with the circuit of FIGURE 3 as in that of FIGURE 5, and also in any of the circuits to be described hereinafter in connection with FIGURES 12, 13 and 15.

In FIGURE 10, only one contact 202 is shown having contact springs 204 and 206 as in FIGURE 3. One end of the contact 204 is extended outside the housing 210 and is provided therewith a magnetic armature 330. On the sewing machine flywheel 218 there is provided a small permanent magnet 332 in such a manner that it will move in a path adjacent the position of the armature 330. As long as the flywheel 218 is rotating with full speed the magnet 332 will not be able to attract the armature 330, but when the speed of the sewing machine 12 is decreased by driving the sewing machine 12 by means of the auxiliary motor 59 the magnet 332 will be able to attract the armature 330 and will thereby open the switch 202 to break the auxiliary motor circuit with the needle in a predetermined position.

Another embodiment of the specific treadle arrangement shown in FIGURE 7 is shown in FIGURE 11. In this embodiment, the main treadle is denoted by reference numeral 250.

The main operating treadle is in the form of a substantially T-shaped plate 250. This plate 250 is pivotally mounted on pins 252 and 254 of which only the left hand pin 252 is shown in full lines. These pins 252 and 254 are supported in bearings 258 and 260, respectively, carried in brackets which, as shown, may be secured by means of screws to the lower cross bar 20 of the sewing machine 12. At the rear end of the plate 250 there is arranged

a spindle 264 the right hand end of which is connected to the operating rod or chain 146 leading to the main motor operating arm 64. It will be understood that by rocking the main plate 250, the sewing machine can be stopped and started in a manner similar to operation of the single treadle 148 in the different embodiments described hereinabove.

The switch operating treadle 250 is combined with switch control treadle plates by providing on the spindle 264 two individual treadle plates P_h and P_v each carried by pairs of brackets 266a and 266b, respectively. On the front end of the plate 250 there is arranged a pin 270 carrying a two-armed rocking lever 268 having ends 268a and 268b, respectively, extending upwardly and so dimensioned that only one or the other of the two plates P_v and P_h can be pressed down at the time.

The two treadle plates P_h and P_v may either be of insulating material or they may have insulating portions carrying contact pins 272a and 272b, respectively, adapted to cooperate, by pressing down either of the treadle plates P_h or P_v , with pairs of contact pins 274a₁₋₂ and 274b₁₋₂. This will bridge one pair or the other of the contact pins and thereby close a circuit in a manner similar to that described in connection with the two treadle plates of FIGURE 7 for actuating the switch U or O.

One circuit in which the treadle arrangement according to FIGURE 11 may be used is shown more specifically in FIGURE 12. The circuit of this embodiment substantially corresponds to the circuit shown in FIGURE 5 with the exception that only single switches m_1 and m_2 are arranged on diametrically opposite sides of the sewing machine flywheel 218. Furthermore, in FIGURE 12, the mechanical arrangement between the main motor 26 and the auxiliary motor 59 has been omitted to simplify the diagram.

As in FIGURE 5, the auxiliary motor 59 is inductively fed from the main motor 26 through three phase leads a , b and c . In these phase leads there is inserted a three-pole switch a_{1-3} controlled by a relay AR, which is inserted in a circuit comprising an extension b' of the phase lead b and an extension c' of the phase lead c . The ends of these two phase lead extensions b' and c' and the contacts 274b₁₋₂ belonging to the right hand treadle plate P_h are also shunted by the switch m_1 . In the phase lead c_1 there is further inserted at X the switch m_2 shunted by the left hand treadle plate contacts 274a₁₋₂.

Operation

The arrangement shown in FIGURE 12 operates as follows:

The treadle is pivoted to decouple or disengage the main motor 26 as described with reference to FIGURE 7. By changing over the clutch, the sewing machine 12 is slowed down and is driven by the auxiliary motor 59. The operation of the treadle is effected by either of the two treadle plates P_v or P_h .

By operating the treadle with the right hand plate P_h , the relay AR is connected into a circuit including the phase leads b' , c' , the switch m_2 and the switch m_1 now shunted by the contacts 274b₁₋₂. When the switch operating member 216, which is shown in the drawing as a centrifugal member but which, within the scope of the invention, may also be a magnetic member as shown in FIGURE 10 or sliding contacts, as shown in FIGURE 8, opens the switch m_1 , opening of switch m_1 , however, will not stop the auxiliary motor 59, because the switch m_1 is short-circuited by the contacts 274b₁₋₂. When however, the switch operating member 216 opens the switch m_2 , this will break the relay circuit with the result that the winding of relay AR is de-energized and the relay contacts a_{1-3} will break or open the energizing circuit for the auxiliary motor 59, stopping the latter with the needle in the selected position, for example, the bottom position thereof.

Conversely, when the left hand treadle plate P_v is used, the contacts 274a₁₋₂ will short-circuit the switch m_2 leaving the contacts 274b₁₋₂ open. This means that

opening of the switch m_2 by the switch operating member 216 will have no influence on opening of the auxiliary motor circuit. The relay will, however, drop out when the switch m_1 is opened by the switch operating member 216 corresponding to a stop of the sewing machine 12 with the needle in the other position, for instance, the top position thereof.

As further shown in FIGURE 11, there may be a switch 276 incorporated in the treadle 250 and having an operating pin 278 extending into a bifurcated portion 280 of the left hand lever arm 268 so as to throw over the switch 276 by pressing the left hand treadle plate P_v .

A treadle arrangement as shown in FIGURE 11, and including this switch 276, 278, may be incorporated in the circuit arrangement shown in FIGURE 13.

This arrangement corresponds to that shown in FIGURE 12 with the exception that the switch 276 is inserted in the two phase leads b and c at KR and is operable in such a manner that these two phase leads are directly connected with the right-hand treadle plate P_h in the bottom position, while the two phase leads are cross-connected when the left-hand treadle plate P_v is in the bottom position.

Operation

If it is assumed that operation of the treadle by means of the right hand plate P_h corresponds to stop of the sewing machine with the needle in the bottom position thereof, while operation of the treadle with the left-hand plate P_v corresponds to stopping the sewing machine with the needle in the top position thereof, it will be understood that the sewing machine by the arrangement shown in FIGURE 13 can be operated in the following manner.

The treadle is operated by the right-hand treadle plate P_h . This will, as in the case of FIGURE 12, stop the machine when the switch m_2 is opened corresponding to the bottom position of the needle. The left hand treadle plate P_v is operated thereafter. This will close the auxiliary motor circuit through the relay AR, because the contacts 274a are now interconnected thereby short-circuiting the open switch m_2 . Simultaneously however, the switch 276 will be operated crossing the phase leads b and c . This means that the auxiliary motor 59 will be started again but now in the reverse direction, will then make half a revolution until the switch m_1 is opened, and will thereafter be stopped with the needle in the top position. This arrangement is useful, for instance, when locking a certain stitch chain in the work.

Instead of incorporating in the treadle arrangement a special switch 276, the arrangement may be as shown in FIGURE 14, which only differs from the arrangement in FIGURE 11 in that instead of the switch 276 the left hand contact set 274a of FIGURE 11 is provided with three contact pins designated in FIGURE 14 by reference numerals 275a₁₋₃.

This arrangement may, for instance, be used as shown in the wiring diagram of FIGURE 15. This wiring diagram differs from the diagram shown in FIGURE 12 only in that between the point x and the third of the three pins 275a₁₋₃ there is inserted a further relay BR having contacts b_{1-2} inserted in the phase leads b and c and operable either to connect the two phase leads b and c directly or to cross-connect these phase leads.

Operation

The arrangement as shown in FIGURE 15 operates in the following manner:

By operating the treadle with the right hand treadle plate P_h , the circuit is closed only through the relay AR. The relay BR is de-energized and assumes a position corresponding to a "straight" or direct connection of the two phase leads b and c . As in the case of FIGURES 12 or 13, the auxiliary motor 59 is stopped with the sewing machine needle in the bottom position thereof upon opening of the switch m_2 .

By pressing down thereafter the left hand treadle plate P_v , the auxiliary motor 59 is again started because the open switch m_2 is thereby short-circuited by the two left-hand contact pins 275 a_1-2 . Simultaneously therewith, a circuit through the relay BR is established by means of the third contact pin 275 a_3 . When this occurs, the relay BR throws over the switch b_{1-2} thereby cross-connecting the phase leads b and c , whereupon the sewing machine motor 59, as in the case of the operation of the switch 276 in FIGURES 11 and 13, is reversed and then again stopped with the needle in top position thereof.

While in the foregoing the means for synchronizing the breaking or opening of the auxiliary motor circuit with the position of the sewing machine needle has been described with reference either to the centrifugal member shown in FIGURES 3 and 4 or the magnetic means shown in FIGURE 10, it will be understood that the invention is not restricted to the use of these specific means, but that other means can be used within the scope of the invention.

As an example of other means, there is shown in FIGURES 16 and 17 an embodiment comprising a plurality of switch tubes. A substantially cylindrical housing 350 has a rear wall 352 and a front wall 354. Three circular concentric contact rings designated by reference characters R_1 , R_2 and R_3 are arranged in the front wall 354. A plurality of switch tubes are arranged within the housing 350. In the embodiment illustrated herein four switch tubes designated by reference characters S_1 , S_2 , S_3 and S_4 are kept in a position extending radially with a suitable angle, such as an angle of 90° between each pair of tubes, by means of partitions designated by reference characters P_1 , P_2 , P_3 and P_4 . The tubes S_1 , S_2 , S_3 and S_4 may be small glass bulbs containing a liquid body such as mercury. From the outer end of each tube there extends inwardly into the interior thereof two electrodes marked E_{41} and E_{42} , as illustrated in connection with the end of the tube S_4 (FIGURE 16).

The over-all mechanical arrangement of the switch of FIGURES 16 and 17 may be as more specifically shown in FIGURES 18 and 19. Reference numeral 356 designates in these figures a bracket secured by screws or the like 358 on the top surface of the sewing machine table 10. The sewing machine 12, as in the other figures, is designated by reference numeral 12. The bracket arm 362 is pivotally mounted on a shaft 360 supported in bracket 356, where it can be adjusted and secured in position. The outer end of arm 362 carries the housing 350, shown in FIGURES 16 and 17. As shown in FIGURE 17, the housing 350 is arranged on a spindle or shaft 364. This spindle 364 is rotatably carried in a bearing 366 (FIGURE 18) provided at the end of the arm 362. A bushing 368 having a radial arm 360 is secured to the other end of spindle 364. A hole provided in the radial arm 360 receives a pin 372 which is secured eccentrically to the sewing machine flywheel 14. From the bearing 366 there also extends an arm or the like 374 carrying a brush holder 376 having three carbon or other brushes B_1 , B_2 and B_3 cooperating respectively with the three contacts rings R_1 , R_2 and R_3 . An electric lead with three conducting wires connects the arrangement with the electric circuit to be more fully described hereinafter.

By mounting the arrangement described herein, care should preferably be exercised to ensure that the axis of the rotating housing 350 is exactly in axial alignment with the axis of the main sewing machine spindle carrying the flywheel 14.

It will be understood that during the rotation of the sewing machine the housing 350 will also be rotated, the movement being transmitted through the pin 372 to the arm 374.

A diagram of the motor drive circuit, in which the arrangement shown in FIGURES 16 to 19 is utilized, is schematically illustrated in FIGURE 20. In this figure,

reference character A_1 , B_1 and C_1 form the main motor stator, and a_1 , b_1 and c_1 the feeding or energizing coils for the auxiliary motor 59, which is inductively fed from the main motor 26 as in FIGURE 6.

Instead of, as in FIGURE 6, connecting the three auxiliary motor stator windings a_1 , b_1 and c_1 directly in a Y-connection, the inner ends of the stators a' and c' are connected through leads d and e with top electrodes D and E of a mercury relay AR_3 the bottom electrode F of which is connected through a lead f with the inner end of the auxiliary motor stator b' .

The relay AR_3 is of the kind comprising an external relay winding A_v containing a cylindrical core C_v normally floating on the mercury but which, upon energization of the relay winding A_v is drawn down to raise the mercury thereby to bridge the three electrodes. Relays of this kind are so well known that a further detailed description of the relay is not believed necessary and is, therefore, dispensed with herein.

In the circuit shown in FIGURE 20, it is assumed that an arrangement along the lines described with reference to FIGURES 16 to 19 is used but comprising only two mercury switch tubes S_1 and S_2 with two contact rings R_1 and R_2 connected respectively with a brush B_1 and B_2 . The brush B_1 is connected with the phase lead b by an extension b_{20} thereof while the brush B_2 is connected through the relay winding A_v with the phase lead a through an extension a_{20} thereof. The two electrodes of the switch tube S_1 , viz E_{11} and E_{12} , are connected with the two contact rings R_1 and R_2 and in a similar manner the electrodes E_{21} and E_{22} of the switch tube S_2 are connected with the two contact rings R_1 and R_2 .

Operation

The operation of the arrangement shown in FIGURE 20 is as follows:

At normal speed, i.e., with full speed of the main motor 26, the centrifugal force will keep the mercury in the two switch tubes S_1 and S_2 at the outer ends of the tubes thereby bridging the respective electrodes E_{11} , E_{12} and E_{21} , E_{22} in the two tubes and thereby short-circuiting the connection between the two contact rings R_1 and R_2 . The direction of rotation of the switch described will be that indicated by the arrow in FIGURE 20. The relay winding A_v is, therefore, connected into the circuit including the leads a_{20} and b_{20} and, accordingly, the core C_v will be in the down position thereof with the mercury connecting the three electrodes D, E and F and thereby interconnecting the three auxiliary motor windings a' , b' and c' so that the auxiliary motor 59 will also be energized and running.

When the main operating treadle is operated and the main motor 26 decoupled or disengaged as described hereinabove, the sewing machine 12 will be driven further by the auxiliary motor 59 but at a reduced speed, which will not be sufficient to produce a centrifugal force, sufficient to hold the mercury in the outer ends of the mercury tubes S_1 and S_2 . This means that when the mercury tube S_1 arrives slightly above the horizontal position the mercury in this tube will flow back to the inner end of the tube S_1 . The same applies to the switch tube S_2 and the flowing back of the mercury in this tube will then break the connection between the two contact rings, R_1 and R_2 which again means that the circuit through the relay winding A_v will be broken with the result that the Y-connection of the auxiliary motor 59 is broken.

As already mentioned hereinabove, the angle between the two mercury switch tubes S_1 and S_2 which are connected in parallel may be approximately 90°. It will be understood from the following, however, that this angle may be varied within certain limits so as to thereby vary the angular position of the sewing machine spindle within which it will be stopped. Generally speaking, there is no sharp angular position of the sewing machine spindle which corresponds to a predetermined needle position so

that it is understood that within a certain range of angular positions of the main spindle, the needle will be in the top position thereof, and within certain opposite range of angular positions of the main spindle, the needle will be in the down position thereof. These angles have to be considered in the designing of the switch arrangement. If only one single mercury switch tube instead of the double-pole type switch as shown had been used, it would be purely incidental or accidental in which position within an angle of 180° the sewing machine spindle was stopped. By providing a double pole switch having two mercury switch tubes S_1 and S_2 shunted in the control circuit for the auxiliary drive and forming a suitable angle therebetween, it will be found that the free angle through which the sewing machine spindle is allowed to rotate when the brake is applied will be 180° minus the angle between the two switch tubes S_1 and S_2 so that, by way of example, when the latter angle is 90° the angle through which the sewing machine spindle is allowed to rotate will also be 90° , which in practice will be sufficient to secure stop of the machine with the needle in a desired position, namely with the needle point either in the work, i.e., in the down position, or free of the work, i.e., in the top position thereof.

The arrangement shown in FIGURE 20 enables the needle to be stopped in a single position, for instance, in top position.

FIGURE 21 shows an embodiment similar to that shown in FIGURE 20, but further including a double plate treadle similar to the one shown in FIGURE 11 and four switch tubes as shown in FIGURES 16 to 19. The extension a_{21} of the phase lead contains the relay winding A_v and is connected to the brushes B_1 and B_2 , respectively. The other phase lead extension b_{21} is connected to the third brush B_3 .

The four contact tubes are interconnected and connected with the three contact rings in the following manner:

Electrodes E_{31} , E_{41} , E_{21} and E_{11} are all connected to the inner contact ring R_3 . The electrodes E_{32} and E_{42} are interconnected and are also connected with the outer contact ring R_1 , while the electrodes E_{12} and E_{22} are interconnected and also connected to the intermediate contact ring R_2 .

It will be understood that by pressing the right hand treadle plate P_h the circuit will be completed through the relay winding A_v , the right treadle contact pins $274b_{1-2}$, the outer contact ring R_1 , switch tubes S_3 and S_4 and inner contact ring R_3 .

This will, in the manner described with reference to FIGURE 20, keep the auxiliary motor 59 running until the mercury in these two tubes S_3 and S_4 , at the reduced driving speed, is no longer held in the outer ends of the tubes S_3 and S_4 . The auxiliary motor circuit will, therefore, be interrupted with the sewing machine needle in one position, for instance, in bottom position thereof.

By pressing the left hand treadle plate P_v , the circuit will be as shown at the bottom of FIGURE 21. The circuit is thereby completed through the phase lead a_{21} , left hand treadle plate contacts $274a_{1-2}$ to intermediate contact ring R_2 through the mercury switch tubes S_1 and S_2 to the inner contact ring R_3 , brush B_3 and through the phase lead b_{21} .

This means that the switch tubes S_1 and S_2 will now take over the control of the position in which the auxiliary motor circuit is broken, and since these tubes are arranged diametrically opposite to the tubes S_3 and S_4 it will be the opposite position, viz the top position of the needle.

It will further be understood that the arrangement shown in FIGURE 21 can be modified so as to include also the possibility of reversing the auxiliary motor 59, for instance, by including a reverse switch in the circuit, as schematically shown in FIGURE 22. In this embodiment, the reverse switch KR is only shown schematically inserted in the phase leads a and c and operable, for ex-

ample, by the treadle in the form of a separate switch as shown in FIGURE 11.

It will be understood, however, that the arrangement according to FIGURE 22 may also be modified to include a further relay to operate the reverse switch in the manner already shown and described with reference to FIGURE 15.

It will be understood that in the foregoing specification many different embodiments have been shown and described.

Although in order to simplify the description, several of the embodiment are shown as incorporating the centrifugally operated cam member, viz that type of switch in which the switch itself is stationary and is operable by a member, which, when the machine is driven at reduced speed, will lie in a path abutting the switch operating member, it is to be understood that in these embodiments the centrifugal switch can be replaced by a rotating switch according to FIGURES 16 to 19, if so desired.

While in the foregoing embodiments of the treadle arrangement, several species have been shown and described in which the pivotable treadle operatively connected with the driven clutch element is provided with treadle plate portions, which are individually pivotable to operate the switch selecting means in order to effect stopping of the auxiliary motor in either of two different predetermined positions, it will be understood that the same can be effected by means of the treadle arrangement shown in FIGURE 23.

In this embodiment, only one treadle plate is used, the two half parts of which are equivalent with each of the two treadle plate portions of the foregoing species. To facilitate the survey of FIGURE 23, the front half part of the treadle plate is cut away and only shown in outline in dash lines. As shown in FIGURE 11, the treadle is supported in brackets 258 and 260 secured to the lower transverse bar 20 of the sewing machine. In these brackets 258 and 260, there is rotatably arranged a shaft 400 extending at one end beyond the bracket 260 and provided therewith a radially extending arm 402 to the end of which at 404 there is linked a ring or bushing 406 connected to the pull-rod 146 shifting the driven clutch element between the driving clutch element and the rotatable brake member. Between the two brackets 258 and 260, there is secured on the spindle 400 a bar 408, which is preferably provided with a shelf-like portion 410. This bar 408 may be of any convenient cross section, but is preferably of rectangular cross section. The bar 408 is provided with a suitable bearing or the like 412 intermediate its ends in which bearing 412 is secured a rod or spindle 414 extending perpendicularly to the spindle 400. The ends of the spindle 414 extend into bearings in brackets 416 and 418, respectively, on which is secured a treadle plate 420.

The bar 408 is secured to the spindle 400 in such a manner that it is not allowed to rotate relatively to the spindle 400. It will be understood that treadle plate 420 is thereby allowed to pivot in two perpendicular directions in a way similar to that in which a compass is suspended. The one movement as represented with the double arrow H will cause a rotation of the spindle 400 thereby shifting the driven clutch element, while a pivoting of the treadle plate in direction of the double arrow K will effect control of the breaking or opening the auxiliary motor circuit in the manner to be described hereinafter.

Two pairs of contacts springs 474a₁₋₂ and 474b₁₋₂ which correspond to the contacts 274a₁₋₂ and 274b₁₋₂ in FIGURE 11 and which extend in opposite directions are arranged on the projecting portion 410 below the treadle plate 420. The contact springs 474a₁₋₂ and 474b₁₋₂ are clamped in insulated supports 470 and 472 respectively. Above each of the contacts 474a₁₋₂ and 474b₁₋₂ there is secured to the top of the insulating supports 470 and 472 an outwardly extending resilient arm or spring

466 and 468, respectively, having at their respective ends abutments 462 and 464. Below these arms or springs 466 and 468 there are furthermore secured insulating knobs or the like 458 and 460, respectively, to engage the upper of the two contact springs in each of the pairs 474a₁₋₂ and 474b₁₋₂.

It will be readily understood that by operating the treadle arrangement of FIGURE 23 with the right foot, the treadle plate will be tilted to the position shown in FIGURE 23, in which the right hand half part of the treadle plate 420 is operative to close the switch 474b₁₋₂. Accordingly, by using this treadle arrangement in any of the circuits described hereinbefore having two switches to be selected to effect stopping of the auxiliary motor 59 with the sewing machine actuating mechanism in one of two predetermined positions, this position of the treadle plate will enable control of the sewing machine auxiliary drive to be stopped in, for instance, the top position. In a similar manner, operation of the treadle plate in FIGURE 23, with the left foot tilting the plate in the direction opposite to that shown, will enable the sewing machine auxiliary drive to be operated to stop the machine with the stitch forming mechanism in the opposite direction.

Having now, by way of example, described different embodiments of my invention, it will be understood that the invention is not limited to the specific examples and may be varied in different respects without departing from the scope of my invention.

Basically, my invention provides in combination with a sewing machine or another machine a clutch motor comprising means for driving the machine at high speed and auxiliary driving means for driving the machine at a reduced speed which is so slow that the stoppage of the machine when driven by the auxiliary drive is completely under control and can be stopped either at will in a predetermined position, for instance, of the reciprocating needle of the sewing machine or automatically in such predetermined position.

Another important feature of my invention resides in the provision of control circuit arrangements including circuit branches and switch means to be controlled automatically in the different manners described to provide automatic stoppage of the machine in a predetermined position of the movable parts thereof.

It will readily be understood that my invention is by no means confined to the specific embodiments illustrated.

The basic point is, however, to provide a clutch motor having a power driven rotatable brake member performing the function of an auxiliary drive, but whether this auxiliary drive acts on or is operatively connected with the driving connection between the driven clutch element and the sewing machine as illustrated and described on the brake member when the latter is in engagement with the driven clutch member or on the clutch member in some other way or elsewhere in the driving connection between the driven clutch member and the sewing machine is of less importance.

It will also be understood that my electric circuits for the auxiliary driving motor and the different embodiments of the automatic control, for instance, by means of the two-way pivotable treadle can be applied in combination with any kind of auxiliary driving motor irrespective of the fact where it acts on or is operatively connected with the driving connection.

I claim:

1. A clutch motor including an electric motor comprising a main driving spindle, a flywheel secured on said spindle, a motor housing supporting said motor with said spindle and said flywheel, an end cover of said motor housing adjacent said flywheel, a brake member rotatably supported in said end cover opposite and spaced from said flywheel, a secondary driving spindle rotatably supported in said end cover, transmission means between

said secondary driving spindle and said rotatable brake member, an output spindle rotatably supported in said end cover having an end extending outside said end cover, a driven clutch element in driving connection with said output spindle, means supported by said motor end cover operable at will to displace said driven clutch element between a first position in which it engages said flywheel and a second position in which it engages said rotatably arranged brake member, and an auxiliary electric motor in driving connection to rotate said secondary driving spindle and thereby said rotatable brake disc.

2. In a clutch-and-brake driving mechanism in combination: a driving power member, a driving clutch element driven at high speed by said power member, a brake member, a driven clutch element disposed between said driving clutch element and said brake member and adapted to be alternately shifted to engage either said driving clutch element or said brake member, means for slowly driving said brake member, a power transmission between said driving power member and said brake driving means including auxiliary clutch means in said power transmission between said driving power member and said brake driving means, and means for operating said clutch means for disconnecting said power transmission.

3. A unitary, self-contained electric motor of the clutch-and-brake type comprising a main driving motor having a main driving spindle comprising a rotor, said spindle having fastened thereon adjacent one end of said rotor a flywheel and adjacent the opposite end of said rotor an auxiliary driving member, a rotatable brake disc in coaxial relationship to and spaced from said flywheel, a driven clutch disc arranged between said flywheel and said brake member in coaxial relationship to either thereof, an output spindle connected with said driven clutch disc to rotate therewith extending from said clutch motor in axial relationship to said main driving spindle, a secondary driving spindle having an extending end, a reduction gear between said secondary spindle and said brake disc, a driving mechanism between said auxiliary member on said main spindle and said secondary driving spindle, clutch means included in said driving mechanism, means for operating said clutch means to effect and terminate rotation of said secondary driving spindle by means of said auxiliary driving mechanism, and means for shifting said driven clutch disc to alternately engage said flywheel and said brake disc.

4. An electric motor of the clutch-and-brake type having a main electric motor comprising a driving spindle, a flywheel secured on said driving spindle, a rotatable brake disc in coaxial relationship to and axially spaced from said flywheel, a reduction gear in driving connection with said rotatable brake disc, an auxiliary driving spindle in driving connection with said reduction gear, a driven clutch disc arranged between said flywheel and said brake disc in coaxial relationship thereto, said driven clutch disc being arranged for axial displacement, an output spindle in driving connection with said driven clutch disc, means operable at will to shift said driven clutch disc to alternately engage said flywheel and said brake disc, an auxiliary electric motor, and a driving connection between said auxiliary electric motor and said secondary driving spindle for said brake disc.

5. In a driving arrangement for a working machine to be driven by a friction clutch motor comprising a main driving clutch motor arrangement including a main driving clutch element driven continuously at high speed, a rotatable brake member, a driven clutch element, means for shifting said driven clutch element to alternately engage said main driving clutch element and said brake member, an electrically controlled auxiliary drive to forcibly rotate said brake member at low speed, a control circuit for said electrically controlled auxiliary drive, said circuit including a voltage source, a switch structure, means for rotating at least a part of said switch structure synchronously with a part of said working machine, means

for operating said switch structure at a predetermined angular position of said part of said working machine to de-energize said control circuit, a treadle arrangement and switch means selectively operated by said treadle arrangement for closing said circuit.

6. A power unit for driving a sewing machine having a main spindle including a high speed driving clutch element, power means for continuously rotating said driving clutch element, a brake element, a driven clutch element, an output spindle connected to said driven clutch element, means for shifting said driven clutch element to alternately engage said driving clutch element and said brake element, auxiliary driving means for slowly driving said brake element, an electric control circuit for said auxiliary driving means including means operable to break said electric control circuit in one angular position of said sewing machine spindle, means operable to break said electric control circuit in another angular position of said sewing machine spindle, means operable at will for selecting either of said control circuit breaking means, and means for rendering effective said circuit breaking means responsive to the speed of said sewing machine when driven by said clutch element in the position thereof shifted to engage said slowly driven brake element.

7. In a driving arrangement for a sewing machine having a stitch forming mechanism including a main spindle and a reciprocating needle, a power unit operatively connected for driving said sewing machine spindle and including a high speed driving clutch element, a brake, a driven clutch element, a transmission to rotate said sewing machine spindle by said driving clutch element, treadle operated means for shifting said driven clutch element to alternately engage said driving clutch element and said brake, auxiliary driving means for slowly driving said brake, an electric control circuit for said auxiliary drive, means operable to break said electric control circuit responsive to one angular position of said sewing machine spindle, means operable to break said electric control circuit responsive to another angular position of said sewing machine spindle, and means operable by said treadle means for selecting either of said control circuit breaking means, said control circuit breaking means including means responsive to the speed of said sewing machine for rendering said control circuit breaking means effective when said machine is driven by said clutch element in the position thereof shifted to engage said slowly driven brake element.

8. A drive for a sewing machine having a main spindle comprising, a high speed driving clutch element, a rotatable brake, a driven clutch element in driving connection with said spindle, means for shifting said driven clutch element to alternately engage either said driving clutch element or said brake, auxiliary rotating means for slowly driving said brake, an electric control circuit for said auxiliary rotating means including means operable to break said electric control circuit in response to the rotation of said sewing machine when driven by said driven clutch elements shifted to the position engaging said slowly driven brake.

9. In combination with a sewing machine having a stitch forming mechanism and including a main spindle and a reciprocating needle: a clutch-and-brake type motor comprising drive means, a driving clutch-and-flywheel disc fastened to said drive means, a brake disc, a driven clutch disc, control means to shift said clutch disc to alternately engage said driving clutch disc and said brake disc, a driven spindle operatively connected with said driven clutch disc, a transmission between said driven spindle and said sewing machine spindle, means for slowly driving said brake disc, an electrical control circuit for said brake disc driving means, switch means in said electric control circuit, and means for operating said switch means in response to rotation of said sewing machine spindle including means operable to activate said switch means responsive to a predetermined angular position of said

sewing machine spindle to de-energize said control circuit for said brake disc driving means.

10. A driving arrangement for a sewing machine having a main spindle and stitch forming mechanism including a clutch motor having an output spindle for driving said sewing machine and a movable clutch element in driving connection with said output spindle to rotate simultaneously therewith, a main driving clutch element on one side of said movable clutch element, a rotatable brake member on the other side of said movable clutch element, means operable to shift said movable clutch element between one position in which it engages said main driving element and another position in which it engages said brake member, auxiliary driving means for driving said brake member at reduced speed to operate as a secondary reduced speed driver for said output spindle when said movable clutch element is in said second position engaging said brake member, electrical control means for said auxiliary driving means operable to energize and de-energize said auxiliary driving means, and means operated by said sewing machine spindle in at least one predetermined position thereof for actuating said electrical control means to de-energize said auxiliary driving means.

11. A driving arrangement for a sewing machine having a main spindle comprising, a friction clutch motor of the type having an output spindle adapted to drive said sewing machine spindle, a driven friction clutch element connected with said output spindle to rotate therewith, a continuously, relatively rapidly rotating main driving friction member, a brake member arranged opposite said driven clutch element that is connected with said output spindle, means for selectively bringing said driven clutch element into engagement with said main driving member to drive said output spindle at high speed and into engagement with said brake member to stop said output spindle, means for rotatably supporting said brake member, and auxiliary driving means for rotating said brake member at reduced speed to slowly rotate said output spindle when said driven clutch element engages said rotatable brake member and the latter is driven by said auxiliary driving means, said auxiliary driving means including electrical control means to selectively render said auxiliary driving means operative to drive said rotatable brake and inoperative to discontinue the rotation of said brake member to stop said sewing machine, and control means for selectively controlling said electrical control means for said auxiliary driving means.

12. A driving arrangement for a sewing machine having a spindle including a modified clutch motor of the type having a main driving member, a brake member and an output spindle for driving said sewing machine spindle including a driven clutch member located between said main driving member and said brake member and selectively shiftable therebetween, comprising auxiliary driving means for said brake member, said brake member being rotatably supported in said motor and in operative driving connection with said auxiliary driving means to be driven slowly therefrom, and electrical control means operatively connected with said sewing machine spindle and operative to control stopping and starting of said auxiliary driving means.

13. A driving arrangement for a sewing machine having a main spindle and including a clutch motor having a driving clutch member, a braking member, a driven clutch member located between said driving clutch member and said braking member and an output spindle operatively connected with said driven clutch member, comprising continuously rotating high speed drive means operatively connected with said driving clutch member, slow speed driving means spaced from and separate from said high speed drive means and operatively connected with said braking member for driving the latter at relatively lower speed, means for alternately and selectively connecting said driven clutch member only with said driving clutch member or said braking member to the exclusion of one another, electrical control means operable to select one op-

erating condition for said low speed driving means to drive said output spindle by way of said driven clutch member at low speed and another operating condition in which said low speed driving means is rendered ineffective to thereby stop the driving of said output spindle, and means operable to control the preselection of said operating conditions.

14. A driving arrangement as claimed in claim 13, in which said electrical control means includes switch means and means for actuating said switch means by said sewing machine main spindle to thereby cause said sewing machine to be stopped in a predetermined angular position of said main spindle in response to the actuation of said switch means.

15. A driving arrangement as claimed in claim 14, in which said switch means have a part rotatably driven by said sewing machine main spindle.

16. A driving arrangement as claimed in claim 14, in which said switch means includes a fluid body movable to one position by the centrifugal force when said sewing machine main spindle is driven by said high speed driving means, and to another position by gravity when said sewing machine spindle is driven by said slow speed driving means.

17. A driving arrangement as claimed in claim 16, in which said fluid body of said switch means is mercury, and at least one mercury switch tube supported to rotate with said rotating sewing machine main spindle.

18. A driving arrangement for a sewing machine having a main spindle and including a clutch motor having an output spindle for driving said sewing machine main spindle, comprising continuously rotating high-speed driving means, slow speed driving means spaced from and separate from said high-speed driving means, means for alternately and selectively connecting only either said high speed driving means or said low speed driving means to said output spindle to the exclusion of one another, electrical control means operable to select one operating condition for said low speed driving means to drive said output spindle at low speed and another operating condition in which said low speed driving means is rendered ineffective to thereby stop the driving of said output spindle, and means operable to control the preselection of said operating conditions, said electrical control means including means operable to reverse the direction of rotation of the sewing machine stitch forming mechanism after stoppage thereof with the needle in one position.

19. A driving arrangement as claimed in claim 18, in which said electrical control means includes means for automatically continuing the drive of said sewing machine main spindle in reverse direction after stoppage thereof to another predetermined position in response to actuation of said reversing switch.

20. A driving arrangement as claimed in claim 19, in which further switch means are provided for actuating said reversing switch automatically.

21. A driving arrangement as claimed in claim 13, in which selector means are provided operable to select means for stopping the machine in one predetermined position and means operable to stop the machine and then reverse it to another predetermined position.

22. A driving arrangement as claimed in claim 13, in which said electrical control means includes at least one switch operable to be actuated in timed relationship with the rotation of said sewing machine main spindle, and an electrical control circuit including said switch in one branch, and wherein said control means further includes a reverse control switch and another branch of said circuit including said reverse control switch.

23. A driving arrangement as claimed in claim 22, in which said one switch is arranged to be actuated to open said control circuit in response to a predetermined angular position of said sewing machine main spindle to de-energize said control circuit, and in which said reverse control switch is operable to energize an auxiliary circuit

branch to reverse the direction of rotation of said slow speed drive means.

24. A driving arrangement as claimed in claim 18, further comprising treadle means operable to select said high speed driving means and said low speed driving means, and in which said reverse control switch is associated with said treadle means.

25. A driving arrangement as claimed in claim 13, in which said slow speed driving means include power means, in which said electrical control means includes means to interrupt the power input to said power means, and in which said slow speed driving means includes reversing means.

26. A driving arrangement as claimed in claim 13, in which said high speed driving means and said slow speed driving means are driven from the same source.

27. A unitary clutch motor with common support and housing means for driving a sewing machine including an electric motor having a main driving disc member, a brake disc rotatably supported within said common support and housing means opposite said main driving disc member, auxiliary driving means within said common support and housing means for driving said brake disc at reduced speed to serve as a secondary reduced speed driving member, a driven clutch disc located within said common support and housing means between said main driving disc member and said brake disc, means operable for shifting said driven clutch disc to alternately engage said main driving disc member and said brake disc, and a transmission spindle connected with said shiftable clutch disc for rotation in unison therewith, at least one of said brake disk and said auxiliary driving means including means operatively connected therewith to effectively constitute said brake disk a braking member operative to selectively stop said driven clutch disk upon engagement thereof with said brake disk.

28. The improvement of an essentially instantaneously operating stop-and-start unitary friction clutch motor of the type including a fast rotating driving friction disc, a brake disc supported opposite said driving disc and a driven spindle having a friction clutch disc shiftable between a position engaging said driving disc and a position engaging said brake disc comprising, said driving friction disc, said brake disc and said friction clutch disc being arranged substantially coaxially and being freely rotatable relative to one another with said friction clutch disc disengaged from both said driving friction disc and said brake disc, means supporting said brake disc rotatably in said motor, and auxiliary driving means operatively connected with said brake disc to rotate the same at a lower speed compared with the speed of said fast rotating driving disc, at least one of said stationary brake disc and said auxiliary driving means including means operatively connected therewith to effectively constitute said brake disc a brake member operative to selectively stop said driven friction clutch upon engagement thereof with said brake disc.

29. In a unitary friction clutch motor the combination comprising, a power member, a primary driving friction member in continuous rotation driven by said power member at a substantially constant high speed, a friction brake member rotatably supported opposite said primary driving member in substantially fixed spaced relationship thereto, a single driven friction member supported for displacement in the space between said primary driving member and said brake member, an output spindle driven by said driven friction member, means for displacing said driven friction member between a first position in which it engages said primary driving member and a second position in which it engages said rotatable brake member, and auxiliary driving means including a reduction gear operable to rotate said rotatable brake member at low speed to act as a reduced speed driver for said driven friction member upon engagement thereof with said brake member during rotational movement thereof, at least one of said friction brake member and said auxiliary driving

means including means operatively connected therewith to effectively constitute said friction brake member a brake operative to selectively stop said driven friction member upon engagement thereof with said friction brake member.

30. A clutch motor as claimed in claim 27, in which said brake disc together with at least a part of said auxiliary drive means constitutes a unit provided with means for securing said unit in proper location opposite the main driving clutch member.

31. A clutch motor as claimed in claim 27, in which said brake disc is connected with said auxiliary drive means through a reduction gear.

32. A clutch motor as claimed in claim 31, in which said reduction gear is a self-locking worm gear.

33. A clutch motor as claimed in claim 31 in which said housing means has means to secure the same to said motor with said driven clutch disc opposite said main driving disc member to enable engagement of said driven clutch disc when disengaged from said rotatable brake disc.

34. A clutch motor as claimed in claim 33, in which said housing means is in the form of an end cover of an electric motor constituting the main driving motor.

35. A clutch motor as claimed in claim 27, in which said auxiliary drive means includes a member rotatable jointly with said main driving disc member, and a driving connection between said member rotating jointly with said main driving member and said brake disc including an auxiliary clutch.

36. A clutch motor as claimed in claim 27, in which said auxiliary driving means includes an electric motor inductively fed from said main driving motor.

37. A clutch-and-brake driving mechanism comprising a fast rotating main driving clutch element, a rotatable brake, a single, axially shiftable driven clutch element disposed between said driving clutch element and said brake, means for shifting said driven clutch element to alternately engage either said driving clutch element or said brake, auxiliary drive means for slowly driving said brake, and means effective to operatively disconnect said auxiliary drive means and to positively stop said brake to thereby also stop indirectly said driven clutch element upon engagement thereof with said brake.

38. A driving arrangement for a machine having a rotatable element comprising a clutch motor having output means for driving said machine and a movable clutch element in driving connection with said output means to rotate simultaneously therewith, a main driving clutch element on one side of said movable clutch element, a rotatable brake member on the other side of said movable clutch element, means operable to shift said movable clutch element between one position in which it engages said main driving element and another position in which it engages said brake member, auxiliary drive means for driving said brake member at a reduced speed to operate as a secondary reduced speed driver for said output means when said movable clutch element is in said second position engaging said brake member, control means for controlling said auxiliary drive means for selectively putting the same into or out of operation, and means responsive to at least one predetermined position of said rotatable element for actuating said control means.

39. A driving arrangement according to claim 38 further comprising means for supplying power to said auxiliary driving means from said clutch motor.

40. A driving arrangement according to claim 39, wherein said last-mentioned means includes clutch means.

41. A driving arrangement according to claim 40, wherein said clutch means is operative to enable reversal of the direction of rotation of said auxiliary driving means.

42. An electric power source for a sewing machine which enables the operator to stop the machine with the needle bar in a pre-elected dead position, the said power source comprising an electric motor having an extended

motor shaft, a first coupling element fastened to one end of said motor shaft, a second coupling element adapted to move in and out of operative contact with said first coupling element mounted at the coupling shaft end adjacent to said first coupling element, spring tension means adapted to keep the said second coupling element out of contact with the said first coupling element, a braking element adapted to operatively contact said second coupling element, a sheave for driving the sewing machine attached to the free end of the said coupling shaft, a lever adapted to be connected at one end to the foot control of the sewing machine and linked at the other end to means counteracting the spring tension and moving the said second coupling element into operative contact with the said first coupling element when the

5 said lever is moved into one position and moving the said second coupling into operative contact with said braking element when the said lever is moved into the opposite position, auxiliary driving means for said braking element, and circuit means including an interrupter 10 adapted to act in synchronism with the rotation of the sewing machine for supplying power to said auxiliary drive means and keeping the said auxiliary drive means energized and for cutting the power to said auxiliary driving means when the sewing machine attains a pre-elected 15 point of rotation.

43. In a control mechanism for a sewing machine having a rotatable part with at least one predetermined angular home position, a main high speed driving member for normally driving the part at high speed; means 20 sequentially rendering the main driving member ineffective to drive the rotary part, retard the rotary part gradually, drive the part at a speed substantially less than that of the main driving member and finally stopping the rotary part in the predetermined angular home position; said means including braking means journaled for rotational movement with the rotary part and adapted gradually to retard the rotary part when initially connected therewith, a slow speed auxiliary driving member 25 operatively connected with the braking member to drive the braking member at a predetermined low speed, an electrical circuit for controlling the operation of the auxiliary driving member, operator-influenced means for rendering the main driving member ineffective to drive the rotary part, means movable synchronously with the 30 rotary part, and the electrical circuit including means cooperative with the synchronously movable means and effective only when the rotary part has been driven by the auxiliary drive member to the predetermined angular home position to render the auxiliary driving member ineffective to rotate the rotary shaft.

44. In a driving mechanism for a sewing machine or the like of the type having means for driving the machine at a predetermined high-speed, means for driving the machine at a reduced speed and means for stopping the 35 machine with its parts in a predetermined position, including a rotatable main clutch disk, an auxiliary clutch disk, means for driving said auxiliary clutch disk at a reduced speed, a shiftable clutch disk shiftable to selectively engage either said main clutch disk or said auxiliary clutch disk, a transmission between said shiftable clutch disk and said machine, and means operable at will to shift said shiftable clutch disk, the improvement comprising: a unitary friction clutch motor including an 40 electrical main motor, a main clutch disk driven from said main motor, a brake disk, a clutch disk disposed between said main clutch disk and said brake disk and shiftable between said main clutch disk and said brake disk to selectively engage only one of said disks at any time, an output connected with said shiftable clutch disk, 45 mechanical means operable at will for shifting said shiftable clutch disk, means operative to enable said brake disk to rotate, auxiliary drive means for rotating said brake disk, actuating means for selectively rendering said auxiliary drive means effective to rotate said brake disk 50

or for rendering said auxiliary drive means ineffective to thereby discontinue rotation of said brake disk and thereby render said brake disk effective as a stationary brake including means operable for positively halting said shiftable clutch disk with said actuating means rendered ineffective to drive said brake disk.

45. A driving mechanism as claimed in claim 44, in which said halting means is constituted by said brake disk itself when said actuating means renders said auxiliary drive ineffective to rotate said brake disk so that the latter constitutes a stationary brake.

46. A driving mechanism as claimed in claim 44, wherein said auxiliary drive means includes a driven member and means for driving said driven member from said main motor, and further comprising selectively engageable and disengageable clutch means between said driven member and said brake disk.

47. A driving mechanism as claimed in claim 44, wherein said auxiliary drive means includes selectively energizable and de-energizable electrical drive means, an energizing circuit including a voltage source for said electrical drive means, means for rendering said auxiliary drive effective to drive said brake disk including a contact operable at will in said energizing circuit, and means for rendering said auxiliary drive means ineffective to drive said brake disk including contact means having a part thereof rotating with said machine and a switch operable to be opened in said predetermined position of said machine, said switch being inserted in said energizing circuit in series with said switch operable at will so as to open said circuit to thereby de-energize said electrical drive means when said switch operable at will is closed.

48. A driving mechanism as claimed in claim 47, further comprising switch-operating means operable to close said switch operable at will in response to actuation of said mechanical means operable, at will, to shift said shiftable clutch disk, said switch-operating means being operable to close said switch operable at will in response to operation of said actuating means to disengage said shiftable clutch disk from said main clutch disk.

49. A driving arrangement for driving a machine such as a sewing machine and the like at a normal speed and at a speed relatively slower with respect to said normal speed and for selectively stopping the same in a predetermined position, comprising a clutch motor unit provided with common support and housing means including a main driving disk, an auxiliary driving disk, a shiftable clutch disk between said two driving disks operatively connected in both the normal and relatively slower speeds with said machine for rotating the latter and adapted to be shifted in the axial direction thereof for direct engagement in a first position thereof with said main driving disk and in a second position thereof with said auxiliary driving disk, first driving means for driving said main driving disk at said normal speed, second driving means for selectively driving said auxiliary driving disk at said reduced speed or for effectively constituting said auxiliary driving disk a braking member to thereby selectively drive said shiftable clutch disk at said reduced speed or brake the same upon engagement of said auxiliary driving disk with said shiftable clutch disk in said second position of the latter, and actuating means for selectively shifting said shiftable clutch disk in the axial direction into said first or second position, said common support and housing means supporting and encasing therein at least said driving disk, said auxiliary driving disk and said shiftable clutch disk, and means rotatably supporting all of said disks and said driving means in said common support means.

50. A driving arrangement according to claim 49, wherein said machine includes rotating switch means operative to control said auxiliary driving means.

51. A driving arrangement according to claim 50 further comprising an energizing circuit including said ro-

tating switch means so as to automatically energize and de-energize said energizing circuit for said auxiliary driving means upon rotation of said machine.

52. A driving arrangement according to claim 51, wherein said rotating switch means is operative to open said energizing circuit in a predetermined position of said machine to thereby stop the same in said predetermined position by stopping said auxiliary driving means.

53. A driving arrangement according to claim 52, wherein said auxiliary driving disk is effective as a brake disk for said shiftable clutch disk upon engagement therewith with said machine in said predetermined position.

54. A driving arrangement according to claim 51 further comprising means for closing said energizing circuit upon actuation of said actuating means to disengage said shiftable clutch disk from said main driving disk.

55. A power unit for driving a sewing machine having a main spindle including a high speed driving clutch element, power means for continuously rotating said driving clutch element, a brake element, a driven clutch element, an output spindle connected to said driven clutch element, means for shifting said driven clutch element to alternately engage said driving clutch element and said brake element, auxiliary driving means for slowly driving said brake element, an electric control circuit for said auxiliary driving means including means operable to break said electric control circuit in one angular position of said sewing machine spindle, means operable to break said electric control circuit in another angular position of said sewing machine spindle, and means operable at will for selecting either of said control circuit breaking means.

56. A power mechanism for driving a sewing machine having a rotary shaft, comprising a frame, an electric motor having a rotor shaft journaled in the frame, a driven power take-off shaft journaled in the frame, a friction brake journaled in the frame for rotational movement, power transmission means adapted for operatively connecting the power take-off shaft with the sewing machine rotary shaft, operator-influenced means mounted on the frame to connect the power take-off shaft operatively with either the rotor shaft or the friction brake, means operatively connected with said friction brake for rotating the friction brake at a speed substantially less than that of the rotor shaft, an electrical circuit for controlling the operation of the friction brake, and means included in the electrical circuit which when actuated is effective to render the friction brake ineffective to rotate the power take-off shaft.

57. A power drive mechanism which comprises support means, an electric motor having a rotor shaft journaled in said support means, a driven power take-off shaft journaled in said support means, a friction brake journaled in said support means for rotational movement, operator-influenced means connected with said support means to connect the driven power take-off shaft operatively with either the rotor shaft or the friction brake, means mounted on said support means and adapted to rotate the friction brake at a speed substantially less than that of the rotor shaft, an electrical circuit for controlling the operation of the friction brake, and means included in the electrical circuit which when actuated is effective to render the friction brake ineffective to rotate the power take-off shaft.

58. In a control mechanism for a sewing machine in combination, main driving means with energizing means therefor, a rotary part rotatable with and adapted to be driven by said main driving means, braking means journaled for rotational movement with said rotary part and adapted to cooperate with said rotary part gradually to retard the machine, slow speed driving means operatively connected with the braking means to drive the braking means at a speed slower than the speed of the main driving means, an electrical circuit for controlling the opera-

tion of the low speed driving means, operator-influenced means for rendering the main driving means ineffective to drive the rotary part and for preparing the electrical circuit for controlling the low speed driving means, and means movably synchronously with said machine, the electrical circuit means including means cooperative with said synchronously movable means and effective when the circuit has been prepared and the rotary part has been driven by said low speed driving means to a selected angular position to render the slow speed driving means ineffective to rotate the rotary part.

59. A unitary, self-contained electric clutch-brake power transmitter having frame means, comprising in combination an electric motor with a rotor, means rotatably supporting said rotor within said frame means, a clutch including a single driving clutch member operatively connected with said rotor, a single brake member, and a driven clutch member disposed between said driving clutch member and said brake member and adapted to selectively engage with either said single driving clutch member or with said single brake member, output means operatively connected with said driven clutch member, means rotatably supporting said driven clutch member, said output means and said brake member within said frame means, slow speed drive means for said single brake member supported on said frame means and operative to constitute said single brake member either a direct-acting slow speed drive member or a direct-acting stationary brake member for said driven clutch member upon engagement of the latter with the former, and means supported on said frame means for selectively shifting said driven clutch member into engagement with either said single driving clutch member or with said single brake member.

60. A unitary, self-contained electric clutch-brake power transmitter according to claim 59, wherein said slow speed drive means includes means for positively holding said brake member stationary upon discontinuance of the slow speed drive means.

61. A unitary, self-contained electric clutch-brake power transmitter according to claim 60, wherein said last-mentioned means is a self-locking worm-wheel drive arrangement.

62. An electric power source for a sewing machine which enables the operator to stop the machine with the needle bar in a preselected position, the said power source comprising an electric motor having an extended motor shaft, a first coupling element fastened to one end of said motor shaft, a coupling shaft, a second coupling element adapted to move in and out of operative contact with said first coupling element mounted at the coupling shaft end adjacent to said first coupling element, spring tension means adapted to keep the said second coupling element out of contact with the said first coupling element, a single slow speed driving element adapted to operatively contact said second coupling element, a sheave for driving the sewing machine attached to the free end of the said coupling shaft, a lever adapted to be connected at one end to the foot control of the sewing machine and linked at the other end to means counteracting the spring tension and moving the said second coupling element into operative contact with the said first coupling element when the said lever is moved into one position and moving the said second coupling element into operative contact with said slow speed driving element when the said lever is moved into the opposite position, and means operatively connecting said slow speed driving element to said motor shaft to effectively drive said slow speed driving means by said motor shaft including clutch means interposed in said last-mentioned connecting means to enable selective disengagement of the driving connection between said single slow speed driving element and said motor shaft.

63. An electric power source for a sewing machine which enables the operator to stop the machine with the needle bar in a preselected position, the said power source comprising an electric motor having an extended motor shaft, a first coupling element fastened to one end of said motor shaft, a coupling shaft, a second coupling element adapted to move in and out of operative contact with said first coupling element mounted at the coupling shaft end adjacent to said first coupling element, spring tension means adapted to keep the said second coupling element out of contact with the said first coupling element, a single braking element adapted to be driven at relatively low speed and to operatively contact said second coupling element, a sheave for driving the sewing machine attached to the free end of the said coupling shaft, a lever adapted to be connected at one end to the foot control of the sewing machine and linked at the other end to means counteracting the spring tension and moving the said second coupling element into operative contact with the said first coupling element when the said lever is moved into one position and moving the said second coupling element into operative contact with said braking element when the said lever is moved into the opposite position, and means operatively connecting said braking element to said motor shaft to effectively drive said braking means by said motor shaft including clutch means interposed in said last-mentioned connecting means to enable selective disengagement of the driving connection between said single braking element and said motor shaft.

64. A sewing machine driving arrangement comprising a unitary self-contained electric clutch-brake power transmitter having frame means, comprising an electric motor with a rotor, means rotatably supporting said rotor within said frame means, a clutch including a driving clutch member operatively connected with said rotor, a single slow speed driving member, and a driven clutch member, means for selectively shifting said driven clutch member into operative engagement only either with said driving clutch member or with said slow speed driving member, output means operatively connected with said driven clutch member, means rotatably supporting said driven clutch member, said output means and said slow speed driving member within said frame means, slow speed drive transmission means for said slow speed driving member supported on said frame means and operatively connecting said slow speed driving member with said electric motor to drive the former by the latter, said slow speed drive transmission means including clutch means, and means adapted to operate said clutch means in a predetermined position of said sewing machine to render said slow speed driving transmission means ineffective to drive said slow speed driving member.

65. In a sewing machine driving arrangement for stopping the sewing machine with its stitch-forming mechanism in a predetermined position, in combination: a unitary driving motor comprising a continuously rotating electric motor, a high-speed driving mechanical clutch element connected to said electric motor, a brake effectively operable as a stationary mechanical brake, a shiftable mechanical clutch element, means operable at will to shift said mechanical clutch element between said high speed clutch element and said brake, an electrically controlled auxiliary driving means in said friction clutch motor, means operable to drive said shiftable clutch element relatively slowly by said auxiliary driving means when said shiftable clutch element is disengaged from said high-speed driving clutch element, and electrical control means operatively connected with said sewing machine and operable in response to said desired position of said stitch-forming mechanism to de-energize said auxiliary driving means and simultaneously render said brake operable to positively provide stationary mechanical brake action for said shiftable clutch element.

66. A unitary driving and stopping device for driving and then stopping a shaft of a machine in a predetermined position in response to the will of the operator, said device comprising a frame carrying a primary electric motor having a rotor shaft with a driving element of a clutch directly connected thereto, a brake spaced from and arranged parallel to said driving element, said brake being rotatably carried by said frame, a second electric motor connected to rotate said brake, a driven clutch element disposed in the space between the driving clutch element and the brake, manually controlled means for selectively moving said driven clutch element into engagement with either the driving clutch element or the brake, electrically controlled means for energizing said second motor to cause it to drive the brake when said driven clutch element is disengaged from the driving clutch element and automatic means under control of the angular speed and position of said machine shaft for applying at a predetermined point of its rotation a 15 braking action to the shaft of said second motor.
